FRANCIS A. STERRY, OF CANTON, MASSACHUSETTS.

Letters Patent No. 71,809, dated December 3, 1867.

IMPROVEMENT IN SPINDLE-BOLSTER.

The Schedule referred to in these Letters Patent and making part of the same.

TO ALL WHOM IT MAY CONCERN:

Be it known that I, FRANCIS A. STERRY, of Canton, in the county of Norfolk, and State of Massachusetts, have invented a new and useful Improvement in Spindle-Bolster; and I do hereby declare that the following is a full, clear, and exact description thereof, which will enable others skilled in the art to make and use the same, reference being had to the accompanying drawings, forming part of this specification.

This invention relates to the manner in which the spindle of a cotton-spinning frame is lubricated in the bolster; and it consists in forming an annular recess in the top part of the bolster, in which is placed an absorbent for the oil, and also in cutting slits through the central portion of the bolster, through which the lubricating-oil passes to the spindle, as will be hereinafter described.

Figure 1 represents a vertical section of the spindle passing through the bolster, and of the bolster attached to the rail of the spinning-frame, it being through the line $x x$ of fig. 2.

Figure 2 represents a top view of the bolster with the cap off.

Similar letters indicate corresponding parts in the drawing.

A is the spindle; B is the bolster; C is the spinning-frame rail; D is the cap of the bolster. As will be seen in the drawing, the upper portion of the bolster, which sets upon the rail, is recessed by turning out an annular groove, a , leaving a central portion immediately around the spindle. This central portion is slit or divided into two or more parts, the slits extending from the top of the part to its base, or nearly so. The absorbent or capillary substance which is placed in the recess a , does not entirely fill the recess, but a space is left around the outside of it for the oil. The absorbent is a soft, fibrous substance, cylindrical in shape, or cut out in rings, which fit tightly over the central part, so that the oil is strained through it before it reaches the spindle. The cap D screws into or on to the bolster, with a flange around it, as seen in the drawing, and the flow of oil through the absorbent and the slits is governed by its position. By unscrewing it the air enters and occasions the oil to flow faster than when it is screwed tightly down on to the bolster. When thus screwed down it makes a tight joint, entirely excluding the air. By adjusting it as described, it acts the part of a valve, increasing or diminishing the quantity of oil used on the spindle.

What I claim as new, and desire to secure by Letters Patent, is—

1. The absorbent or strainer in the bolster B, consisting of rings fitting snugly around the slotted central part of the bolster, and placed in the annular recess a , and of less diameter than said recess, whereby the lubricant surrounds the circumference only of the absorbent and is strained through said absorbent to the spindle, as herein shown and described for the purpose specified.

2. In combination with the absorbent or strainer, as described, placed in the recess a , the screw-cup D, fitting air-tight upon the top of the bolster, whereby a valve is produced, which, by screwing up or unscrewing, regulates the quantity of oil to be strained through the absorbent to the spindle, as herein set forth for the purpose specified.

FRANCIS A. STERRY.
